UNITED STATES PATENT OFFICE.

JAMES LIGHTFOOT SHORROCK, OF ACCRINGTON, ENGLAND, ASSIGNOR TO ENTWISLE AND KENYON LIMITED, OF ACCRINGTON, ENGLAND.

CARPET SWEeper.

Application filed July 27, 1921. Serial No. 487,939.

To all whom it may concern:

Be it known that I, JAMES LIGHTFOOT SHORROCK, a British subject, residing at Accrington, county of Lancaster, England, 5 have invented certain new and useful Improvements in Carpet Sweepers, of which the following is a specification.

This invention relates more particularly to the comb like appliance or clearer of 10 carpet sweepers for the clearing or removing from the rotary brush of hairs, fibres, threads, ravellings and similar material which have a tendency to accumulate around the bristles of the brush.

15 It consists of a comb like clearer of trough shape stamped in a single strip of sheet metal with narrow tines or teeth along both edges to enter the bristles so suspended from the top of the sweeper case to rock or 20 slide from side to side as the brush rotates in one direction or the other so that the tines or teeth along the edge towards which the brush is rotating will work downwards or into and enter between the bristles and 25 those along the other edge will simultaneously rock upwards or slide away from the bristles, and in the particular construction of such appliance.

The invention will be fully described with 30 reference to the accompanying drawings.

Fig. 1 is a longitudinal section through carpet sweeper showing one form of the invention.

Fig. 2 is a sectional plan of same.

35 Fig. 3 is a transverse section.

Fig. 4 is a perspective view of part of the comb appliance or clearer D.

Fig. 5 is an enlarged transverse sectional elevation of same.

40 Figs. 6 and 7 are a perspective view and transverse section respectively showing another method of suspending the comb appliance or clearer D.

Figs. 8 and 9 are a perspective view and 45 transverse section respectively showing another method of suspending the comb appliance or clearer D.

Figs. 10 and 11 are a perspective view and transverse section showing another method 50 of supporting the comb appliance or clearer D.

Figs. 12 and 13 are a perspective view and transverse section showing another method 55 of supporting the comb appliance or clearer D and a variation in the form of teeth.

Fig. 14 is a transverse section of sweeper showing another form of the invention.

Fig. 15 is a perspective view of same.

Fig. 16 is a perspective view of another method of supporting the comb appliance 60 or clearer D.

The carpet sweeper is of ordinary construction with a rotary brush A mounted within a casing B rotated by driving wheels C with which a pulley c on the hub is in frictional contact and delivering the sweepings into tray a.

70 The comb appliance or clearer D is stamped in a single piece of sheet metal of trough or somewhat trough shape, that is, with a base d and a series of tines or teeth d' disposed like flanges along both edges, and is suspended from the top of the case B to rock or slide to one side or the other to draw the teeth or tines d' at the side of 75 the clearer towards which the brush A is rotating into the bristles and simultaneously to withdraw the teeth or tines at the opposite side from the bristles of the brush.

A lath or bar E of wood is fitted to the 80 interior of the case B and the comb appliance or clearer D is suspended therefrom.

In the construction shown in Figs. 1 to 5 the clearer D is stamped in a single piece of sheet metal and longitudinally of the base 85 d, a wire d² is soldered or otherwise attached to stiffen it, the ends of the wire extending at both ends to form pivots upon which the clearer may rock. To the lath or bar E brackets e are affixed at both ends 90 in which the pivot ends of the wire d² are journaled. The brackets e may extend downwards to form thread catchers or clearers e' for the ends of the brush A.

In the construction shown in Figs. 6 and 95 7 the clearer D is stamped in a single piece of sheet metal with a longitudinal stiffening wire d² projecting at the ends and pivoted in brackets e and supported at intervals by staples e³ driven into the lath E, or the 100 brackets e may be dispensed with and the rocking suspension be effected by the staples e³ alone.

In the construction shown in Figs. 8 and 9 the clearer D is stamped in a single piece 105 of sheet metal and is suspended by staples d² affixed thereto which pass over a longitudinal wire d³ placed in a groove in the bar E.

In the construction shown in Figs. 10 110

and 11, the clearer D is stamped in a single piece of sheet metal in which holes or slots are formed at intervals and suspended on the heads of screws e^4 screwed into the bar 5 E which is preferably curved or rounded on the underside.

In the construction shown in Figs. 12 and 13 the clearer D is made from a base d to which the teeth or tines d' are affixed by 10 solder or otherwise and it is suspended by staples e^3 which embrace the longitudinal wire d^2 .

In the construction shown in Figs. 14 and 15 the clearer D is stamped in a single piece 15 of sheet metal with slots d^6 , and is supported on screws screwed into the bar E and is free to move laterally from side to side on the screws.

In the construction shown in Fig. 16 the 20 clearer D is stamped in a single piece of sheet metal with projecting lugs d^6 at the ends. To the bar E brackets e are affixed at both ends with slots e^4 into which the lugs d^6 project and by which they are 25 supported. The brackets e extend downwards to form thread catchers or clearers for the ends of the brush A.

The tines or teeth d' of the clearer D are 30 preferably stamped or pressed out of the flat metal bent to the desired inclination and then twisted to bring the edge of each into a plane at right angles to the longitudinal axis of the clearer, as shown in Figs. 4 to 35 11, and 16, or they may be stamped flat as in Fig. 15, or they may be pins of the desired shaped attached to the base as in Figs. 12 and 13.

The end clearer e' for the end of the brush A may form part of the end bracket e of the 40 bar E and be fixed, or as part of the clearer D and rock or slide with it.

When the sweeper is in operation the 45 pressure or friction of the brush A as it rotates will tilt the clearer D or cause it to move laterally to bring one set of tines or teeth d' clear or practically clear of the bristles and will simultaneously draw the other set more deeply into the bristles to separate and remove the threads, hairs or 50 the like which have wrapped round the brush.

What I claim as my invention and desire to protect by Letters Patent is:—

1. In a carpet sweeper the combination 55 with the rotary brush of a comb like clearer therefore comprising a device of approximately trough shape stamped in a single piece of sheet metal extending the entire length of the brush and provided with a

flat base and narrow tines projecting at an 60 inclination at both edges, and means by which it is loosely suspended from the top of the sweeper case and free to move from side to side of the brush as it rotates in one direction to bring the tines along the edge 65 towards which the brush is rotating into engagement between the bristles and those along the other edge out of engagement with the brush.

2. A clearer for the rotary brush of carpet sweepers comprising in its construction a comb like clearer of approximately trough shape stamped from a single piece of sheet metal and provided with narrow teeth along both edges, a longitudinal wire extending 70 along the centre to stiffen it and end supports by which to suspend it from the top of the sweeper case so as to be free to move from side to side as the brush rotates in one direction or the other so that the tines or teeth along the edge towards which the brush is rotating will work downwards or into and enter between the bristles, and those along the other edge will simultaneously work upwards or away from the 75 bristles substantially as described.

3. A comb like clearer for the rotary brush of carpet sweepers constructed of approximately trough shape stamped in a single piece of sheet metal with narrow 80 teeth along both edges, and each tooth twisted at right angles to bring a narrow edge into the path of the rotary brush and locking device to suspend it from the top of the sweeper case so as to be free to rock 85 from side to side substantially as and for the purpose described.

4. A clearer for the rotary brush of carpet sweepers comprising in its construction a double comb of trough shape with teeth 90 along both edges stamped in a single piece of sheet metal, a stiffening and supporting wire attached thereto, and end brackets 95 in which the comb is pivoted and upon which it is free to permit it to rock from side to side as the brush rotates in one direction or the other to bring first one set of teeth and then the other set of teeth into contact with and between the bristles of the brush substantially as described.

In testimony whereof I have hereunto set my hand in presence of two subscribing witnesses this 8th day of July, 1921.

JAMES LIGHTFOOT SHORROCK.
